(57) **CLAIM**

The ornamental design for a modem, as shown.

DESCRIPTION

This object is used for connecting a personal computer and a telephone set to a VDSL network in an apartment house, especially on a so-called home side of a VDSL system.

FIG. 1 is a front elevational view of a modem showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view of thereof.
